(57) **CLAIM**

We claim the ornamental design for the double sided safety light, as shown and described.

DESCRIPTION

FIG. 1 is a bottom view of a double sided safety light showing our new design;

FIG. 2 is a front view thereof;

FIG. 3 is a right side view thereof, the left side view being the same as said right side view;

FIG. 4 is a top view; and,

FIG. 5 is a perspective view.
